(57) **CLAIM**

The ornamental design for a raceway for cable management, as shown and described.

DESCRIPTION

FIG. 1 is an isometric view of the design for a raceway for cable management in accordance with a preferred embodiment of the present invention;

FIG. 2 is a top view of the raceway for cable management of FIG. 1;

FIG. 3 is a bottom view of the raceway for cable management of FIG. 1;

FIG. 4 is a side view of the raceway for cable management of FIG. 1; and,

FIG. 5 is a rear view of the raceway for cable management of FIG. 1.

Portions of the design shown in broken lines form no part of the claimed design.
